UNITED STATES PATENT OFFICE

FRITZ ALLENDORFF, OF STUTTGART, GERMANY, ASSIGNOR TO ROBERT BOSCH AKTIEN-
GESELLSCHAFT, OF STUTTGART, GERMANY

MAGNETO ELECTRIC IGNITION APPARATUS

Application filed December 5, 1931, Serial No. 579,336, and in Germany December 10, 1930.

The invention relates to magneto electric ignition apparatus in which springs, for example, for contacts and the like, are arranged in proximity to the high tension winding. It has been found that such springs, at the points which lie nearest to the high tension winding, become very much oxidized under the action of the silent discharges which proceed from these coils, owing to the nitrogen oxide which is produced by the discharge. The nitrogen oxide in combination with moisture forms nitrous acid, which attacks the springs, so that they break comparatively soon at the places in question. According to 15 the invention, this drawback is removed by the springs being surrounded by a metallic sheath.

An example of construction of the invention is illustrated in the drawing, in which:—
20 Figure 1 is a view of an armature of a magneto in part section.

Figure 2 is an end elevation of the armature cover.

In the drawing 1 denotes the armature cover or shroud of a magneto armature. In this latter a condenser 2 is provided in known manner which is held by spring pressure plate 3 in the recess 4 of the armature cover. This pressure plate is screwed to lugs 5 on 25 the armature cover. A copper sleeve 6 encloses the pressure plate, and owing to the pressure of the plate 3 on the condenser is held firmly in position. The sleeve 6 is made by a ribbon of copper helically wound round 30 about the plate 3. The armature cover 1 is screwed in known manner to the armature pole shoes 7 between which the armature winding 8 is placed. The distance of the pressure plate 3 from the high tension winding 8 is kept as small as possible with a view 35 to the best utilization of space.

By reason of the enclosing copper sleeve 6 the formation of nitrous acid is removed from the surface of the spring 3 to the surface of the metallic sleeve because an electric field originating from the coil can no longer exist within this sheath. Any charge on the sleeve 6 flows to earth through the spring 3.

45 I declare, that what I claim is:

50 1. A magneto including a condenser, a

high tension winding, a spring holding said condenser, and a metallic sleeve enclosing said spring.

2. A magneto including a condenser, a high tension winding, a leaf spring holding 55 said condenser, and a copper sleeve enclosing said spring and maintained in position thereby.

3. An ignition device including a high tension winding a spring near to the said winding, and a metallic sleeve enclosing said spring.

In testimony whereof I have hereunto affixed my signature.
